CARL ERIC ANDERSON, OF STRATFORD, CONNECTICUT, ASSIGNOR TO THE BRYANT ELECTRIC COMPANY, OF BRIDGEPORT, CONNECTICUT, A CORPORATION OF CONNECTICUT.

ROTARY SNAP SWITCH.

Application filed September 11, 1923. Serial No. 662,095.

To all whom it may concern:

Be it known that I, CARL ERIC ANDERSON, a citizen of the United States of America, residing at Stratford, in the county of Fairfield and State of Connecticut, have invented certain new and useful Improvements in Rotary Snap Switches, of which the following is a specification.

My invention relates to rotary snap switches, and particularly to a simple and inexpensive escapement mechanism for the switch.

In the accompanying drawings—

Fig. 1 is a vertical section through a switch in which my invention is embodied in one form;

Fig. 2 is a dropped perspective of certain of the switch parts;

Fig. 3 is a plan view of the escapement parts in one position;

Fig. 4 is a similar view showing the parts in another position; and

Figs. 5 and 6 are vertical sections through the base showing different methods of mounting the bearing plate.

The present escapement mechanism is applicable to switches of various sizes and types, and is illustrated merely by way of example in a single-pole double-break switch, it being understood that the invention is not in any way limited to this particular type of fitting.

The mechanism is mounted upon an insulating base 15 which is pierced at 16 and 17 to accommodate the lead wires which pass therethrough and are secured to the combined wire terminal and switch contacts 18 and 19 mounted upon the upper face of the base. The rotary switch bar 20, which makes and breaks connection with the switch contacts, is mounted on a carrier plate 21 freely journalled on the rotary switch spindle 22. It is subject to the torsional stress of the switch spring 23, one end of which is engaged by the drive plate 24 held in fixed position with respect to the spindle by the bushing 25. The latter is provided with a threaded stem 26 which passes through the switch cover 27,

and receives the thumb piece 28 which is 50 screwed thereon.

The switch bar carrier 21 is engaged by the upwardly angled lug 29 of the detent 30, said lug entering and playing in a radial slot 31 in the plate 21. The detent 55 30 surrounds and is actuated by the cam 32 fast with the spindle 22 and forming a bearing therefor. Cooperating with the detent 30 is a stop plate 33 blanked out to afford a series of internal ratchet teeth 60 34 adapted to be successively engaged by the nose 35 of the detent 30.

Underlying the ratchet plate 33 is a centrally apertured bearing cup 36 preferably formed from sheet metal and having 65 offset margins 37 to receive and closely confine the ratchet plate. A central depression 38 is preferably provided around the aperture of the cup to accommodate the head of a hollow bushing 39 by which the 70 cup is secured in a non-circulating recess 40 in the upper face of the base. When the base is of porcelain, as in Fig. 1, the bushing 39 passes therethrough and is headed at 75 41 in the well 42 in the lower face of the base. When the base is formed of composition the bushing 41 may be molded therein. It is possible to omit the bushing entirely, provided the well or recess in the upper face of the base is sufficiently accurately 80 formed to the non-circular contour of the cup 36. This is indicated in Fig. 6, in which the bearing cup 43 is provided with a central boss 44 entering a well 45 formed in the upper face of the base to accommodate 85 the lower end of the spindle 22.

It will be noted that in any case the spindle is not held in position beneath the base by the usual securing means, but has free bearing in the bushing and is supported on 90 the bearing cup 36 by the cam 32 which is fast with the spindle and projects laterally from the latter, thus forming a shoulder which constitutes a step bearing for the spindle. The spindle is retained against 95 displacement upwardly by a bridge piece 46 centrally apertured at 47 to fit over the bushing 25 on the spindle and bearing

against the drive plate 24. The legs of the bridge are provided with foot pieces 48 apertured at 49 to receive screws by means of which it is secured to the base. The 5 bridge thus not only holds the spindle in position on the base, but forms a bearing spaced from the base and serving to steady the spindle.

The operation of the escapement is readily understood. Upon rotation of the spindle 22 the cam 32 fast therewith, shifts the detent 30 laterally until its nose 35 escapes the ratchet detent teeth 34. During this 10 rotation of the spindle, the spring 23 is stressed and upon the escape of the nose 35 from the ratchet teeth 34 the carrier plate 21, switch bar 22, and detent 30 are rotated by the spring. The detent journalled on 15 the cam 32, which is now relatively stationary, moves outward and halts the rotation of the parts by the impingement of its nose 35 against the succeeding ratchet tooth.

Various modifications in form of the 20 escapement parts and in the general switch structure will readily occur to those dealing with the problem, which do not depart, however, from what I claim as my invention.

I claim—

30 1. In a rotary snap switch, a rotary switch spindle, a switch bar freely mounted thereon, a detent operatively associated with said switch bar, a punched out stop plate within which said detent is arranged, a 35 series of stop teeth formed around the internal margin of said plate and cooperating with said detent, a cam rigid with the spindle and lying in the plane of the detent and stop plate, said cam engaging the detent 40 and serving on the rotation of the spindle to shift the detent out of engagement with the teeth of the stop plate, an insulating base, and a bearing plate mounted on the face of the base and underlying and engag- 45 gaging said stop plate.

2. In a rotary snap switch, an escapement mechanism comprising a fixed sheet metal stop plate apertured within its margins to afford a series of internal stops, a bearing 50 plate underlying said stop plate, a detent lying in the plane of said stop plate and cooperating with the internal stops of the latter, a rotary switch spindle, a cam fast thereon and on which said detent is journalled, said cam and detent resting on said bearing plate.

3. In a rotary snap switch, an escapement mechanism comprising a fixed sheet metal stop plate apertured within its margins to afford a series of internal stops, a cup-shaped bearing plate underlying said stop plate, a detent lying in the plane of said stop plate and cooperating with the internal 60 stops of the latter, a rotary switch spindle, a cam fast thereon and on which said de-

tent is journalled, said cam and detent resting on said bearing plate.

4. In a rotary snap switch, an escapement mechanism comprising a fixed sheet metal stop plate apertured within its margins to afford a series of internal stops, a cup-shaped bearing plate underlying said stop plate, a detent lying in the plane of said stop plate and cooperating with the internal stops of the latter, a rotary switch spindle, a cam fast thereon and on which said detent is journalled, said cam and detent resting on said bearing plate, together with means for securing the cup-shaped bearing plate to the base. 70 75 80

5. In a rotary snap switch, an escapement mechanism comprising a fixed sheet metal stop plate apertured within its margins to afford a series of internal stops, a bearing plate underlying said stop plate, a 85 detent lying in the plane of said stop plate and cooperating with the internal stops of the latter, a rotary switch spindle, a cam fast thereon and on which said detent is journalled, said cam and detent resting on 90 said bearing plate, the latter being apertured to permit the switch spindle to pass therethrough.

6. In a rotary snap switch, an insulating base recessed on its upper face to afford a 95 non-circular well, a bearing plate resting in said well and centrally apertured to accommodate a switch spindle, a rotary spindle accommodated in said central aperture in the bearing plate, a cam fast on said spindle and resting on the upper face of said bearing plate, a detent surrounding said cam and also resting on said bearing plate, together with a stop plate resting on said bearing plate and aperture to afford a series of internal stops surrounding said 100 105 detent.

7. In a rotary snap switch, an insulating base recessed on its upper face to afford a 110 non-circular well, a bearing plate resting in said well and centrally apertured to accommodate a switch spindle, a rotary spindle accommodated in said central aperture in the bearing plate, a cam fast on said spindle and resting on the upper face of said bearing plate, a detent surrounding said cam and also resting on said bearing plate, together with a stop plate resting on said bearing plate and apertured to afford a series of internal stops surrounding said 115 120 detent, together with means rigid with the base for securing said bearing plate thereto.

8. In a rotary snap switch, an insulating base recessed on its upper face to afford a 125 non-circular well, a bearing plate resting in said well and centrally apertured to accommodate a switch spindle, a rotary spindle accommodated in said central aperture in the bearing plate, a cam fast on said spindle and resting on the upper face of 130

said bearing plate, a detent surrounding said cam and also resting on said bearing plate, together with a stop plate resting on said bearing plate and apertured to afford a series of internal stops surrounding said detent, together with a bridge piece secured to the base and engaging the spindle at a point remote from the base to steady the spindle and maintain it and its associated parts in definite relation to the base. In testimony whereof I have signed my name to this specification. 10

CARL ERIC ANDERSON.
